UNITED STATES PATENT OFFICE.

LAURENCE POWELL HUFSTEDLER, OF TULSA, OKLAHOMA.

ATTACHMENT FOR PIPE MACHINES.

1,405,784.

Specification of Letters Patent. Patented Feb. 7, 1922.

Application filed July 9, 1920. Serial No. 394,881.

To all whom it may concern:

Be it known that I, LAURENCE P. HUFSTEDLER, a citizen of the United States, and a resident of Tulsa, in the county of Tulsa and State of Oklahoma, have invented certain new and useful Improvements in Attachments for Pipe Machines, of which the following is a specification.

My invention is an improvement in attachments for pipe machines, and has for its object to provide an attachment of the character specified, adapted to be arranged between the dies and the chuck of a pipe machine, for cutting the pipe at such point, wherein a ring 10 is provided for attachment to the die frame, the said ring having means for carrying a cutter, and having means for adjusting the cutter toward and from the axis of the pipe.

In the drawings:

20 Figure 1 is a side view of a portion of the pipe machine provided with the attachment, Figure 2 is a front view of the ring and frame,

Figure 3 is a section on the line 3—3 of

25 Figure 2,

Figure 4 is a section on the line 4—4 of Figure 3,

Figure 5 is a perspective view of the cutter,

Figure 6 is a view looking from the out-30 side of the die frame with parts broken away.

The present embodiment of the invention is shown in connection with a pipe machine of the Bignaul and Keeler types, having the bed 1, the die supporting frame 2, and the 35 chuck 3, and the attachment is supported by the die frame 2.

The attachment comprises a ring 5, which is secured to the die frame, by means of screws 6 as shown, and there is connected 40 with the ring a guideway 7, the guideway extending radially from one side of the ring. This guideway is recessed on the face adjacent to the chuck, as indicated at 8, and a carriage 9 is mounted to slide in the groove 45 or recess, the walls of the recess being undercut as shown, and the carriage being shaped to fit.

The recess or groove opens at the outer end of the guideway, and a plate 10 is arranged transversely of the said end, to limit the outward movement of the carriage or slide, the plate being detachably held to the guideway by means indicated at 11 in the form of bolts or screws. The inner end of the carriage is concave to 55 correspond with the curve of the inner edge of the ring, and that face of the carriage or

slide which is remote from the ring 5, is recessed as indicated at 12, to receive the cutter blade 13.

The blade rests on a hardened steel plate 60 14 which is arranged directly below the blade or cutter in the recess, and the blade is held in place by a plate 15 which is secured in a rabbet in the guide over the recess. The rabbet is of a depth slightly 65 greater than the thickness of the plate, and extends on both sides of the recess, and the plate is held in place by screws 16.

By loosening the screws 16, the cutter 13 may be adjusted toward and from the pipe 70 4 at the axis of the ring. The carriage is moved by means of a screw 17. This screw is journaled in the plate 10, and it passes through a nut 18 secured to the carriage as shown in Figure 3. The screw is held in 75 the plate by means of a collar 19 mounted on the same just within the plate, and it has a handle 20 at its outer end, for convenience in manipulating the same.

It will be observed that the cutter 13 may 80 be readily removed from the carriage by simply removing the plate 15 thereby exposing the entire cutter. This is made possible since the groove which receives the cutter is formed in the outer face of the carriage 9. 85 Further, it will be noted that the plate 10 which is secured to the end of the guide not only serves as a means for limiting the end-wise movement of the carriage but as a means for causing the carriage to move lon-90 gitudinally when the screw is rotated.

The operation of the construction just described is as follows: With the pipe 4 in place in the machine, when it is desired to 95 cut the same, the carriage is adjusted toward the pipe until the corner of the cutter engages the same. When the pipe is rotated the cutter will gradually cut through the pipe. The attachment does not interfere with the operation of the pipe machine, and the pipe may be threaded and afterwards 100 cut at the proper point.

In Figure 6 the attachment is shown applied to a Peerless machine, the ring 5 being 105 connected with the die frame 21, which supports the dies 22 moved toward and from each other by means of the rod 23. This rod has its ends oppositely threaded, and they are engaged with nuts 24 on the die sections. 110 The construction of the attachment is precisely the same as that shown in Figures 1 and 2, and operates in the same manner.

I claim:

In a machine of the class described, the combination with a pipe receiving member, of a guide secured thereto and having a 5 groove opening out through opposite ends of the guide, a carriage fitted within said groove and having its outer face provided with a groove, a cutter arranged in the groove of said carriage, an elongated plate 10 flatly secured to the outer face of said carriage and engaging said cutter to hold the

same in position, a second plate flatly secured to the outer end of said guide for closing the adjacent end of said first named groove, and means extending through said 15 second named plate and engaged with said carriage for moving the same longitudinally, and a metal plate confined between the lower end of said cutter and the adjacent wall of said second named groove.

LAURENCE POWELL HUFSTEDLER.
